FISHING CRUISER

Richard C. Cole, 19701 Whispering Pines Road,
Miami, Fla. 33157

Filed Aug. 7, 1973, Ser. No. 386,301

Term of patent 14 years

Int. Cl. D12—06

U.S. Cl. D12—62

FIG. 1 is a side elevational view of a fishing cruiser showing my new design.

FIGS. 2 and 3 are top and bottom plan views respectively, and

FIGS. 4 and 5 are rear and front elevational views respectively.

I claim:

The ornamental design for a fishing cruiser, substantially as shown.
